UNITED STATES PATENT OFFICE

136,111

DESIGN FOR A DOUGHNUT OR THE LIKE

Rose Morow, Washington, D. C.

Application April 20, 1943, Serial No. 110,007

Term of patent 14 years

To all whom it may concern:

Be it known that I, Rose Morow, a citizen of the United States, residing at Washington, D. C., have invented a new, original, and ornamental Design for a Doughnut or the like, of which the following is a specification, reference being had to the accompanying drawing, forming part thereof.

In the drawing:

Fig. 1 is a top plan view of a doughnut or the like showing my new design;

Fig. 2 is a front elevational view thereof;

Fig. 3 is a rear elevational view thereof; and

Fig. 4 is an end elevational view thereof.

I claim:

The ornamental design for a doughnut or the like, as shown.

ROSE MOROW.
